US0D1034515S

(12) **United States Design Patent** (10) **Patent No.:** **US D1,034,515 S**
(45) **Date of Patent:** **** Jul. 9, 2024**

(54) **HEADPHONE**

(71) Applicant: **Dyson Technology Limited**, Wiltshire (GB)

(72) Inventors: **Victoria Anne Dorothy Gibson-Robinson**, Gloucester (GB); **William Patrick Shelley**, Bristol (GB); **Jack Cyril Biltcliffe**, Bristol (GB)

(73) Assignee: **Dyson Technology Limited**, Malmesbury (GB)

(**) Term: **15 Years**

(21) Appl. No.: **29/839,491**

(22) Filed: **May 20, 2022**

(30) **Foreign Application Priority Data**

Nov. 23, 2021 (EM) 001483788-0002

(51) **LOC (14) Cl.** **14-01**

(52) **U.S. Cl.**

USPC **D14/205**

(58) **Field of Classification Search**

USPC D14/205, 223, 221; D23/370, 380, 382, D23/412; 2/171.3, 422, 437; 62/259.3,

(57) **CLAIM**

The ornamental design for a headphone, as shown and described.

DESCRIPTION

FIG. 1 is a perspective view of a headphone showing our new design;

FIG. 2 is a first side view thereof;

FIG. 3 is a second side view thereof;

FIG. 4 is a third side view thereof;

FIG. 5 is a fourth side view thereof;

FIG. 6 is a top view thereof; and,

FIG. 7 is a bottom view thereof.

The broken lines depict portions of the headphone that forms no part of the claimed design.

1 Claim, 7 Drawing Sheets
